UNITED STATES PATENT OFFICE.

LOUIS C. HENRIKSEN, OF LOS ANGELES, CALIFORNIA.

DESIGN FOR A BELT-BUCKLE.

No. 38,917.

Specification for Design.

Patented Dec. 3, 1907.

Application filed July 23, 1907. Serial No. 385,225. Term of patent 3½ years:

To all whom it may concern:

I, LOUIS C. HENRIKSEN, a citizen of the United States, residing at Los Angeles, county of Los Angeles, and State of California, have invented a new, original, and ornamental Design for Belt - Buckles, of which the following is a specification, reference being had to the accompanying drawing, forming a part thereof.

The figure is a plan view of a belt buckle showing my new design.

I claim:

The ornamental design for a belt buckle as shown.

LOUIS C. HENRIKSEN.
